BASE DRUM BEATER FOOTPLATE COVER OR SIMILAR ARTICLE

Clifford A. Della-Porta, Evington, England, assignor to
The Premier Drum Company Limited, London, England, a British company

Filed July 5, 1966, Ser. No. 2,914

Term of patent 14 years

(Cl. D56—1)

FIGURE 1 is a top and side perspective view of a bass drum beater footplate cover or similar article, showing my new design.

I claim:

The ornamental design for a base drum beater footplate cover or similar article, substantially as shown and described.
